**ELEVATOR DISCHARGE ORIENTING MEANS
OPERATED IN RESPONSE TO ORIENTATION OF PINS ON THE ELEVATOR**

Howard M. Dowd, Littleton, Royal L. Barrows, Middleton, and Oliver A. Landry, Revere, Mass.; W. Leroy Temple and State Street Bank and Trust Company, executors of said Howard M. Dowd, deceased, said Barrows and said Landry assignors, by mesne assignments, to Otis Elevator Company, New York, N.Y., a corporation of New York

Filed June 6, 1963, Ser. No. 286,015

5 Claims. (Cl. 273—43)

This invention relates to an automatic bowling pinsetting machine. More particularly it relates to an automatic pinsetting machine intended for use with free standing bowling pins, a conventional bowling alley; a machine which has a sufficient degree of flexibility and adaptability in its mode of operation to be useful in connection with the European bowling game known as Kegeln (more familiarly known in the United States as German Nine Pins).

This particular patent is restricted to that portion of the total disclosure that relates to a bowling pin elevator provided with means for orienting the bowling pins upon their discharge from the elevator, said means being actuated by the passage of the pins sequentially in said elevator.

In a generic sense bowling games have developed from a common ancestry into two broad groups. One group as illustrated by bocce or bowls involves rolling a weighted ball across a prepared surface toward a target. The object of such games is to make the ball stop as near to the target as possible. Frequently such games are played out of doors on greens or courts.

In the other broad group the target is an arrangement of upstanding clubs or pins, and the object of the game is to cause a weighted ball to knock over as many of the pins as possible. Such games are for the most part played indoors on lanes or alleys. While there is a variety of games in this second group there have developed over the years rather stringent rules and regulations with respect to each such game governing, among other things, the size, shape and weight of the pins, the arrangement of the pins in the target, the size and weight of the ball and the manner in which the game is played and the score tallied.

In any bowling game where the target consists of an arrangement of pins, and the object of the game is to knock over such pins, a major problem has been the restoration of the pins in the target to their pre-arranged position at the end of each portion of the game, and in some instances where the rules so provide the removal of fallen pins from the alley during the progress of a single portion of the game, usually between the rolling of successive balls. This has required the presence of someone (either one of the players or a person especially employed as a pin boy) at the target end of the alley. Because of the noise of the weighted balls striking the wooden pins, and because of the inherent danger of being struck by a rebounding ball or a flying pin, such work is disagreeable if not dangerous, and as a result it has been increasingly difficult in recent years to obtain persons willing to act as pin boys. In many instances the difficulty in obtaining pin boys has interfered with the normal growth of bowling games.

As the result a great deal of effort has been expended in recent years to develop automatic machinery which would replace the pin boy. To be thoroughly useful such machinery known as pinsetting machines, should be compact enough to fit in the space available in a

2

standard alley; should operate quickly and efficiently with a minimum of supervision and maintenance; should handle and reset the pins and balls in strict accordance with the rules of the particular game; and should not interfere with the normal interaction between the ball and the pins during the playing of the game.

Bowling pins normally have an irregular shape and as a result are difficult to handle. For this reason the early pinsetting machines were of the tethered pin variety wherein the top of each pin was connected by a string to an apparatus arranged directly above the target area. With such a machine the pins are reset merely by pulling on the strings thereby restoring the pin to its upstanding position. Such machines, however, have never really been satisfactory since the string interferes with the free movement of the pin thus interfering with the normal interaction between the balls and the pins and, on occasion, the several strings become entangled and intertwined, thereby interfering with the pin resetting cycle.

In the past decade or so pinsetting machines have been developed and introduced commercially for automatically resetting free standing (as contrasted to tethered) pins in connection with the standard United States bowling games, such as ten pins, candle pins, duck pins and rubber duck pins. Such machines duplicate with remarkable precision the desired activities of a pin boy which they replaced. In general these machines are provided with sweep means for removing the pins from the alley and depositing these pins in the pit normally provided at the rear of the alley; means for separating the pins from the balls; means for elevating the balls and depositing them in the ball-return track normally provided; means for lifting the pins to a position above the end of the alley; means for orienting the pins and distributing them to a reciprocal pinsetting mechanism; means including the reciprocating pinsetting mechanism for placing the pins in the exact desired position on the alley; means including the reciprocating pinsetting mechanism for lifting the still standing pins after a ball has been bowled to permit the fallen pins (the deadwood) to be swept into the pit when the rules so require, and control means for causing the machine to operate upon detecting the passage of a ball or upon command of the bowler.

Contrary to the experience in connection with the standard United States bowling games no automatic pinsetting machines, other than those of the tethered pin variety have to date been developed for use in connection with the popular European bowling game of Kegeln (German Nine Pins). The reason for this appears to lie in the fact that the nine pin game involves two different sizes of pins simultaneously, king size and common pins, and that over the years a variety of different games have developed using the same basic target and balls, but with various arrangements of pins in the target and various modes of play. Thus an automatic pinsetting machine designed for resetting free standing pins for German nine-pin bowling must of necessity be a much more flexible, much more adaptable machine than one designed for use with any of the standard United States bowling games.

In German nine pin bowling according to the regulations established by the German Bowling Association (Deutscher Kegler Bund) the target is of a diamond shape with eight common pins arranged in the form of a square having two opposing corners paralleled with the longitudinal axis of the alley on the center line thereof. A common pin is located on each of the corners of the square and at the mid-point of each side. A king pin is located at the center of the square. Thus the layer of pins in the target is symmetrical and the pins as viewed by the bowler are arranged in five equally spaced parallel

rows with three pins including the king pin arranged along the center line of the alley, a row of two pins on each side of the center row, and a row consisting of one pin each on the outside at each side.

The pins are turned from hard wood with the common pin having a height above the base of 40 cm., a maximum diameter of 10 cm. with a generally barrel-shaped lower section and a necked in upper section. More specifically the diameter of the pin at the base is 6.5 cm. and the thickness of the pin increases on a smooth curve above the base until at a point 5 cm. above the base the diameter is 10 cm. The 10 cm. diameter continues to a point 16 cm. above the base at which point the pin is necked in to a minimum diameter of 5 cm. at a point 26.5 cm. above the base. Above this point the pin widens out again terminating in a semi-hemispherical cap having a diameter 8.6 cm. with the top of the pin located as stated above at a point 40 cm. above the base. The king pin is identical with the common pin except that its semi-hemispherical cap is further provided with an upstanding arm having a minimum diameter of 3 cm. and a height of 40 cm. above the base, a maximum diameter of 4.5 cm. at 41.5 cm. and a flat top at 43 cm. above the base.

Pins of both varieties are provided with a ball having a diameter of 17.5 mm. which protrudes from the bottom of the base at the center line of the pin for a distance of 6 mm. This ball fits into a corresponding socket provided in the alley floor at the exact position prescribed for the desired array. This ball which protrudes from the base serves two functions to ensure that the pin is exactly located in the array and to prevent the pin from sliding out of position. The distance that the inset ball protrudes is such that the pin is substantially out of balance unless that ball is located in a corresponding socket.

The ordinary bowling ball used for German nine pin bowling has a substantially larger diameter than the maximum diameter of the pin being about 19 cm. in diameter as compared to 10 cm. For comparison it is somewhat larger than the small balls used for such United States games as candle pins, but are substantially smaller than a full size "ten pin" ball.

A major distinction between the United States bowling game and the German nine pin game is that a number of different games with a different mode of play have been developed all of which can be played on a single alley without changing the pins or the balls in the German nine pin game. To win the approval of the Deutscher Kegler Bund an automatic pinsetting machine must have the capability of setting pins automatically for at least five of these games as follows:

Voll—in this game a complete set of nine pins is reset after each roll of the ball.

Wiederholen Spick—in this game any combination of any numbers of the nine pins may be selected. The pre-selected combination of pins are reset after each roll of the ball until such time as a new selection is desired.

Handspick—in this game any combination of any number of the nine pins may be selected. The ball may be rolled as often as desired and the fallen pins (the deadwood) are removed after each roll of the ball. The pins are reset at the bowler's request, and upon being reset the bowler may again select any combination of pins.

Abraemen—in this game a full array of nine pins are used and the ball is rolled as often as necessary to fell all of the pins. The deadwood is removed after each roll of the ball and the entire array is replaced after the last pin is felled.

Autom-spick—this game is the same as Abraemen except that the full array is replaced not only when the last pin is felled but also when all of the pins other than the king pin have been felled.

It should be noted that in the pin selection games (Wiederholen Spick and Handspick) while a free choice of pins must be allowed for, the location of the pins is never changed. Thus a king pin is never placed in the position normally occupied by a common pin but rather is always placed when called for in the king pin position in the center of the array. It is also to be noted that in the normal selections a plurality of pins, usually three or more, are used.

5 10 We have developed an automatic bowling pinsetting machine of the general type described above which has sufficient latitude and flexibility to permit this machine to be used with German nine pin bowling in accordance with the requirements set forth by the Deutscher Kegler Bund. 15 It will be understood of course that even though this machine is described in terms of the requirements of the specific German Nine Pin game the improved pinsetting machine and many of the components thereof may be used in conjunction with other bowling games including, but not limited, to the four standard United States games merely by adjusting the size and shape of the various elements to accommodate the different pins and balls and the different arrays and numbers of pins.

20 In the drawings:

25 FIG. 1 is a side elevation partially in section and partially in phantom showing the entire automatic pinsetting machine assembly.

FIG. 2 is a top view of the pit and turntable assembly showing in cross section the pin and ball elevators.

30 FIG. 3 is a partial front elevation showing the drive mechanism of FIG. 2.

FIG. 4 is a side elevation of the pin elevator.

FIG. 5 is a front elevation of the pin elevator.

FIG. 6 is a side view of the pin orienting assembly.

35 FIG. 7 is a sectional view of the assembly shown in FIG. 6 along line 7—7.

FIG. 8 is a side elevation of the king pin separator assembly.

40 FIG. 9 is a front view of the right hand separator unit of the assembly of FIG. 8.

FIG. 10 is a side view of the unit of FIG. 9.

45 FIGS. 11, 12 and 13 are each side elevations of the king pin conveyor assembly showing the drive mechanism therefor at different stages of the pinsetting machine's operating cycle.

FIG. 14 is a top view of the common pin distributor unit.

50 FIG. 15 is a side view partially in section showing a common pin holder and the pin release mechanism attached thereto.

FIG. 16 is a side view partially in section showing the pin release mechanism actuating mechanism.

FIG. 17 is a top view of the index drive mechanism.

55 FIG. 18 is a side view of the index drive mechanism.

FIG. 19 is a top view showing in detail the means for actuating the drive clutch of the index drive mechanism when a pin is inserted in a common pin holder.

60 FIG. 20 is a detailed side elevation of the drive clutch—timer clutch assembly of the index drive mechanism.

FIGS. 21—24 are each a top view of the drive clutch—timer clutch assembly and the associated cams and cam followers during the various portions of the cycle of operation of the common pin distributor.

65 FIGS. 25—28 are each a perspective view of the drive clutch—timer clutch assembly generally corresponding to FIGS. 21—24.

70 FIG. 29 is a plan view of the pin storage section dump plate.

FIG. 30 is a plan view partially in section of the pinsetter assembly.

75 FIG. 31 is an elevation in section of line 31—31 of FIG. 30.

FIG. 32 is an elevational section along line 32—32 of FIG. 30.

The overall machine is shown schematically in FIG. 1 in which the bowling alley is indicated at A, the conventional pit area at the rear of the alley at B, and the wall conventionally located at the edge of the alley alongside the pit and target area at C. The machine generally consists of a sweep mechanism D, a rotating pin and ball separator or turntable E, a ball elevator F, a pin elevator G, a king pin conveyor H, a common pin conveyor I, a common pin distributor J, a pin storage rack K, a reciprocating pinsetting mechanism L, and a sweep and pinsetting mechanism drive means M. The switches and relays for controlling the apparatus are contained in the box indicated at N. The pins are indicated at P_c for common pins and at P_k for king pins. The turntable E and the elevators F and G are designed to fit into a conventional pit B and the remainder of the pinsetting mechanism is designed to rest on the top of the pair of conventional pit walls C.

GENERAL OPERATION

The machine is designed so that each operational function is carried out more or less independently of each other. Sweep mechanism D and the pinsetting mechanism L operate together in the manner described in detail in Dowd and Barrows Patent No. 3,063,716, issued November 13, 1962. This portion of the mechanism is actuated by the passage of a ball down the alley by means of a ball detecting switch (not shown). This switch preferably comprises a photoelectric cell and a corresponding light source arranged on opposite sides of the alley at a height whereby the light beam is broken by the passage of a ball and about one and one-half feet in front of the front pin. Alternatively the ball detector switch may comprise an inertia switch mounted on the padded bumper which is normally pivotally mounted above pit B beyond the end of alley A for the purpose of deflecting flying balls and pins into the pit. In this latter instance the switch is actuated by the sudden movement of the padded bumper.

Sweep D and pinsetting mechanism L have two alternate sequences or cycles, a setting cycle and a deadwood cycle. In the setting cycle the sweep D moves downwardly and rearwardly as soon as its drive mechanism is actuated by the ball detector switch, to the level of the alley and then moves along the level of the alley to the pit pushing any pins that may be located, whether fallen or standing, in the target area into the pit. As soon as sweep D reaches the pit it reverses its direction and returns to a position still next to the alley just in front of the pinsetting mechanism where it stops and acts as a ball guard to prevent the pinsetting mechanism L, the pie, from being damaged if a ball is rolled while pie L is depressed.

As soon as sweep D is out of the way pie L which has been loaded with the desired number of pins is lowered a full stroke to the vicinity of the alley floor and the pins are released onto the alley floor. As soon as the pins are released pie L is retracted and sweep D is returned to its initial position above and in front of the target area.

In the deadwood cycle when the ball detector switch is actuated sweep D moves downwardly and backwardly to the ball guard position next to the alley floor in front of pie L. Pie L is depressed a partial stroke with the pin receiving sockets in an open position until the sockets surround the neck of the pins. The sockets are then closed and the pie L is retracted lifting the standing pins up away from the alley floor. As soon as the standing pins have been lifted above the alley floor sweep D continues its movement toward the pit sweeping the fallen pins into the pit and returns to the ball guard position where it again stops. As soon as sweep D stops again pie L is depressed the same part stroke where the base of the pins contained therein contact the alley releases the retained pins and thereafter pie L and sweep D both return to their initial position.

As set forth in our Patent No. 3,063,713 mentioned above common control means M is so arranged that sweep D and pie L can be driven through either the resetting cycle or the deadwood cycle interchangeably in any sequence, the selection of the cycle being possible until the actual start of the cycle. Since none of the regular German games is played with deadwood (fallen pins) on the alley one cycle or the other is initiated every time the ball detector switch is actuated. In addition to other controls the bowler's position is provided with a pin setting switch which switch will initiate the setting cycle at the bowler's command.

The floor of the pit B is provided with a constantly rotating turntable E which, in connection with baffles overlying turntable E, separate the pins from the balls and direct the pins to pin elevator G and the balls to ball elevator F. Both turntable E and ball elevator F move continuously and ball elevator F lifts the balls from the floor of the pit B and dumps them one by one into the conventional ball return track (not shown) for return by gravity to the bowler's position.

Pins P_c and P_k are lifted one by one by pin elevator G past a king pin separator which deflects the king pins P_k from the elevator. Upon being separated from the elevator pins P_k fall through a pin orienter onto king pin conveyor H. Common pins P_c pass through the king pin separator to the top of pin elevator G where they are deflected from elevator G through a pin orienter onto common pin conveyor I. In both instances the pin orienter causes the pin to fall base first onto the pin conveyor so that the pin travels along the conveyor base first.

King pin conveyor H carries successive king pins P_k directly to the king pin position in the pin storage rack K. King pin conveyor H is provided with a feed section and a delivery section and appropriate drive means are provided to feed successive king pins P_k one by one into the storage rack K when such a pin is needed, and to stop the conveyors and especially the delivery portion when the king pin position in rack K contains a king pin or when the king pin is not required in the particular game. The feed section of conveyor H is driven from pin elevator G and the delivery section from sweep mechanism D.

Common pin conveyor I delivers common pins P_c one by one to rotary common pin distributor J where the pins are deposited upright in separate common pin receiving pockets. The drive of the pin distributor J is so arranged that the pin distributor advances one pocket each time a pin is fed into a pocket or when the pocket coming under the end of conveyor I already contains a pin. Conveyor I is driven by elevator G and switches activated by distributor J are provided to stop both elevator G and conveyor I when additional pins are not required by distributor J.

Pins P are transferred by gravity from distributor J into storage rack K and from storage rack K onto pinsetting mechanism L. Alternate means are provided whereby pins may be released from distributor J into rack K one by one or as a unit depending on whether the selective bowling game has been selected or not. Interlock means are provided to prevent the pins from being released from distributor J into storage rack K until storage rack K is empty ready to receive the pins. Other interlock means are provided to prevent the discharge of pins P from storage rack K onto pinsetting mechanism L until pinsetting mechanism L is in its pin receiving position, is empty of pins, and the sweep and pinsetting control means M calls for the next cycle to be a pinsetting cycle.

As can be seen from this brief description of the general operation of the machine, and from the detailed description of the component parts which follows, the bowling pinsetting machine of the present invention obtains an extreme degree of flexibility of operation primarily by simplifying the component parts. In general

each portion of the machine is designed to perform a single function and to perform that function with a high degree of precision and dependability. Each portion carries out its own function automatically and independently of any other portion of the machine controlled primarily by the presence or absence of a pin or ball in a certain control position at a certain time. At the same time the machine has the inherent capability of an almost unlimited number of sequences of operation. Five are normally provided to correspond to the five standard games as established by the German Bowling Association. While the operation of the machine is entirely automatic the bowler does have a choice of games (i.e. of sequence of operation of the machine) the option to select any pin or any combination of pins in bowling games calling for pin selection and means to reset the machine by running it through a cycle if desired.

Turntable E

As shown in FIG. 2 the floor of pit B is replaced by a turntable 41. Turntable 41 is circular in shape, oriented generally horizontally, but with an outward downward slope toward the edges from a crown at the center and is mounted at its center on a vertical shaft. A circular friction surface, such as a piece of carpeting, indicated at 42 is mounted on the surface of turntable 41 preferably off center as shown. The diameter of turntable 41 is as large as may be conveniently located in the standard pit B and is surrounded by a stationary masking structure 43 which extends to the wall 44 of pit B. Masking structure 43 in each portion slopes from wall 44 towards turntable 41 sufficiently that pins or balls falling onto mask 43 will tend to roll towards turntable 41. Ramps 45 and 46 are provided at the corners of pit B adjacent alley A with a sharper slope toward turntable 41, than the slope of mask 43 to prevent pins from jamming into these corners. A similar ramp 47 is provided along the side wall 44 adjacent pin elevator G for the same purpose. Pin elevator G is mounted in one rear corner of pit B and wall elevator F in the other.

Turntable 41 is rotated continuously by a drive which consists of motor 48, drive belt 49, pulleys 51 and 52 mounted on a vertical shaft 53, second drive belt 54, pulley 55, mounted on vertical shaft 56 which in turn through a pulley (not shown) drives belt 57 which drives pulley 58 mounted on the mounting shaft for turntable 41. The drive for ball elevator F is taken from a second pulley 59 mounted on the top end of shaft 56 by means of belt 61 which passes around pulleys 62 and 63 and passes around a pulley mounted at the top end of ball elevator F. It will be noted that the several pulley combinations all serve as speed reducers in order to keep the rotation of turntable 41 and the greater advance of ball elevator F at a reasonably low rate. As mentioned above, motor 48 in normal operation is powered continuously while the machine is in operation. A separate cut-off switch is provided if, for any reason it is desired to stop turntable 41 or elevator F.

Both pin elevator G and ball elevator F comprise a parallel pair of chain belts which run vertically over two pairs of horizontally separated sprockets, one such pair being located below the level of turntable 41 in each case, the other at the top of the respective elevator. The parallel chains are connected at intervals by horizontal rods. The chain belts and rods of ball elevator F are indicated at 64 and 65 respectively, and of the pin elevator G at 66 and 67 respectively. The lateral distance between chains 64 of ball elevator F is slightly greater than the diameter of the ball, and the lateral distance between chains 66 of elevator G is slightly greater than the over-all height of the king pins. Both elevators are run so that the cross rods 65 and 67 move upward in the front and downward in the rear. The front and rear are separated by vertical walls indicated at 68 in the

case of ball elevator F, and indicated at 69 in the case of pin elevator G, located sufficiently behind the plane of upward movement of cross bar 65 in the case of ball elevator F, and cross bar 67 in the case of pin elevator G, that the center of gravity of a ball or of a pin as the case may be is just slightly behind the respective cross bar toward the aforesaid vertical wall. Tapered internal vertical guides 71 and 72 are further provided for ball elevator F at the sides between the plane of cross rods 65 and rear wall 68 to steady the ball in its upward movement on the elevator. Exterior guides 73 and 74 for elevator F, and 75 and 76 for elevator G are provided outside of both sides of the upward side of both elevators with slots to receive the conveyor chains, and to maintain the respective chains at a fixed clearance from the rear wall.

Separation of the balls and the pins is facilitated by the fact that the ball (indicated at 77) has a substantially greater diameter than the diameter of the pins. A transverse baffle 78 is provided across turntable 41 above and behind the center thereof. The clearance between turntable 41 and the bottom of baffle 78 is at all places sufficient to clear a pin lying on its side on the turntable. The clearance, however, is insufficient to clear a ball except on the left hand side (turntable 41 as shown rotates clockwise) so that a ball once it passes into the rear section is trapped and cannot pass out. A supplemental baffle 79 is provided in front of the entrance to the pin elevator G, and has an insufficient clearance to pass a ball. This prevents the ball from jamming the entrance to the pin elevator. A second supplementary baffle 81 is provided on the rear of baffle 78 near the center of the right side to deflect ball 77 towards the entrance 82 to ball elevator F. Entrance 82 to ball elevator F comprises two elements located slightly above the plane of turntable 41 separated by a distance slightly greater than the diameter of ball 77. Inner element 83 extends out over turntable 41 and acts to deflect pins away from the entrance. Outer element 84 extends to a point adjacent the periphery of turntable 41 at the rear of baffle 78. The floor of entrance 82 slopes toward elevator F so that once a ball 77 passes into the entrance it will roll into elevator F. Thus a ball landing in the pit will roll on turntable 41, will be carried toward the rear, will be deflected toward the center by the inner portion 83 of entrance 82, will be deflected by baffle 81 toward entrance 82, and when it enters entrance 82 will roll down into ball elevator F and will be carried by the next cross bar 65 to top of elevator F where it is pushed off onto a chute leading to the conventional ball return rail. All that is necessary to remove the ball from the elevator is to provide a sloping forward extension of rear wall 68 which extends sufficiently forward of the plane of the rear wall to cause the center of gravity of the ball to lie in front of cross bar 65.

In the meantime the pins P_c and P_k landing at pit B land on a roll to turntable 41 where they are carried around and around beneath the baffle. Because of the tilt of turntable 41 the pins tend to roll toward the edge. The inner portion 83 of ball entrance 82 acts as a pin selector pushing the pins toward the center of the turntable 41 thereby re-orienting the pins continuously. As the pins go around and around and are re-oriented they eventually, one by one, orient themselves so that the leading end (top or bottom) of successive pins lies at the periphery of turntable 41 along a tangent thereto in a position to enter entrance 85 of pin feed 86. Once one end of the pin enters entrance 85 it is pushed into pin feed 86 by contact with a friction surface 42. Pin feed 86 which is separated from turntable 41 by wall 87 has a floor that slopes toward pin elevator G and is generally parallel to the cross bars thereof. The floor of pin feed 86 lies a substantial distance below the level of turntable 41. The width is substantially the same as the width of the cross bar. Such pin once it is pushed through entrance 85 slides onto the floor of feed 86 where it nec-

sarily (because the pin feed chamber 86 is too narrow for the pin to orient itself otherwise to any substantial degree) lies substantially parallel to the cross bar 67 of elevator G. Since the floor of feed 86 slopes toward elevator G the pin tends to roll toward elevator G. The next cross bar 67 comes up beneath the pin next adjacent the elevator and tends to pick up this pin. If the center of the gravity of the pin is between the plane of bar 67 and wall 69 the pin will stay on the elevator and will reorient itself (if necessary) so that its axis is parallel laterally to both the plane of bars 67 and of wall 69. If it so happens that the particular pin is sufficiently cocked that its center of gravity is outside of the plane of cross bar 67 that pin will fall off the elevator and back into pin feed 86.

Pin elevator G

FIGURES 4 and 5 present a front and side elevation of pin elevator G. Chain guides 75 and 76 are mounted on the face of side walls 91 and 92 of elevator G respectively, and rear wall 69 is mounted between two side walls between the upward and downward flights of conveyor chains 66, 66. Chain 66, 66 pass between a pair of sprockets mounted on roller 93 rotatably mounted at the base of conveyor G between side walls 91 and 92 and a pair of sprockets mounted on drive shaft 94 which in turn is rotatably mounted between the side walls 91 and 92 at the top of the conveyor. A pair of adjustable sprockets 95 and fixed sprockets 96 are provided at the top rear of elevator G to adjust tension of chains 66.

Elevator G is driven by motor 97 which is connected by drive chain 98 to reduction gear 99 which in turn is connected by drive chain 101 to drive sprocket 102 mounted on drive shaft 94. An idle sprocket 103 is provided to adjust the tension of drive chain 101. Motor 97 and reduction gear 99 are mounted on bracket 104 which is mounted to the outside of side wall 92 near its upper end.

Means are provided associated with pin elevator G for detecting and removing the king pins Pk from the elevator, for orienting the king pins and delivering the oriented pins to king pin conveyor H. Means are also provided for removing the common pins Pk from elevator G for orienting the common pins and delivering the oriented pins to common pins conveyor I. Since the king pins are transferred to pin storage rack K, and the common pins are transferred first to common pin distributor J, from which they are released and fall into storage rack K, the king pin separating and orienting means are at an appropriate lower level relative to pin elevator G than the common pin separating and orienting means. Since only common pins pass through the king pin separating means all of the pins reaching the topmost level of pin elevator G are common pins. These can be removed from elevator G merely by providing rear wall 69 with a forwardly extending extension 105 located at an appropriate place on rear wall 69 and extending forward from the plane of rear wall 69 sufficiently to force the center of gravity of common pins Pk from the normal location vertically above a position between the plane of rear wall 69 and of cross rods 67 to a location vertically above a position forward of cross rods 67. As soon as the center of gravity passes in front of the plane of cross rods 67 the pin falls forward out of the elevator. Elevator G and associated means are so arranged that when this happens the pin falls through the pin orienting means indicated generally at 106 onto tapered sloping pin slide 107 and down slide 107 to the common pin conveyor I. Pin orienting means 106 and pin slide 107 are both mounted on brackets indicated generally 108 mounted on the side walls 91 and 92 of elevator G in a position forward of the moving portion of elevator G.

Pin orientor 106

It will be recognized that pin feed 86 merely acts to line the pins P up along an axis generally parallel to the cross rods 67 of elevator G, and that no means are pro-

vided to control the orientation of the pins on the elevator. Thus the pins lie on the elevator in random orientation, some with their head toward the right, some with their base toward the right. It is necessary however that 5 all of the common pins Pk be fed to common pin distributor J in a base down condition. This means that the pins Pk must lie on conveyor I in a base forward position. A means indicated generally at 106 for orienting the randomly oriented pins is provided between the point where the pins are discharged from elevator G and slide 107.

As shown in detail in FIGS. 6 and 7 pin orienting means 106 includes a transverse bracket 109 which is fastened horizontally between side walls 91 and 92 in pin elevator G, and passes across the front of elevator G with sufficient clearance therefrom to permit pins to pass up the elevator freely. Two deflector pin pieces 111 and 112 each comprising an upwardly extending pin portion 113 and 114 and a base portion 115 and 116 respectively are pivotally mounted on the outer surface of bracket 109 and 117 and 118 respectively. Pin portions 113 and 114 extend well above the top of bracket 109 and, as shown in FIG. 7, are bent out at a substantial angle in a direction away from the conveyor. Pin pieces 111 and 112 are 15 connected by a connecting rod 119 pivotally mounted at one end to base portion 115 as indicated at 121, and at the other end as indicated at 122 to base portion 116, thereby causing the two deflected pin pieces 111 and 112 to reciprocate in unison. The length of connecting rod 119 is sufficient clearance therefrom to permit pins to pass up the elevator freely. Two deflector pin pieces 111 and 112 each comprising an upwardly extending pin portion 113 and 114 and a base portion 115 and 116 respectively are pivotally mounted on the outer surface of bracket 109 and 117 and 118 respectively. Pin portions 113 and 114 extend well above the top of bracket 109 and, as shown in FIG. 7, are bent out at a substantial angle in a direction away from the conveyor. Pin pieces 111 and 112 are connected by a connecting rod 119 pivotally mounted at one end to base portion 115 as indicated at 121, and at the other end as indicated at 122 to base portion 116, thereby causing the two deflected pin pieces 111 and 112 to reciprocate in unison. The length of connecting rod 119 is 20 adjustable by means indicated at 123 and 124 and is so adjusted that when one deflector pin is vertically oriented the other is oriented outwardly. Pin pieces 111 and 112 are located on bracket 109 in such manner that when oriented vertically pin portions 113 or 114 will be in line with the neck portion of the bowling pin at a point slightly below the knob of the top of the bowling pin, and the length of connecting rod 119 is adjusted such that when one of the pin portions 113 or 114 is oriented vertically the other pin portion 113 or 114 will clear the base of the pin. Bracket 109 is so located on conveyor G that if pins are 25 discharged from the conveyor they will fall past and through the upwardly extending pin portion in such manner that either pin portion 113 or 114 will contact the bowling pin. A stop 125 and 126 respectively is provided at the lower outer corner of base portions 115 and 116. Stays 125 and 126 cooperate with the lower portion of bracket 109 and prevents pin pieces 111 and 112 from pivoting inwardly beyond the aforesaid vertical position. Thus the left and right deflector pin pieces 111 and 112 30 operate in unison and reciprocate as a unit over a limited path of travel between a position where one or the other is in the path of the upper end of a bowling pin, and where the one which is not in such a position is so located as to permit the base of the bowling pin to pass without interference.

Means for positioning deflector pins 111 and 112 are shown generally at 127. Actuating means 127 includes a bracket 128 mounted on and depending from bracket 109, and a cross rod 129 mounted transversely on the bottom of bracket 128 and extending below and parallel to bracket 109. At each end of rod 129 there is pivotally mounted pin sensing means 131 and 132 respectively.

Each of pin sensing means 131 and 132 comprises a collar 133 and 134 respectively mounted over rod 129, a crank rod 135 or 136 extending inwardly from one end 45 and a second crank arm 137 or 138 extending inwardly from the other end. A connecting rod 139 is pivotally connected at 141 to crank arm 131 and at 142 to the inner lower quadrant of base portion 111. A similar connecting rod 143 is pivotally connected at 144 to crank arm 132 and at 145 to the inner lower quadrant of base portion 112. Adjusting means 146, 147 are provided to adjust the length of connecting rods 139 and 143 respectively. A wheel 148 is rotatably mounted at the end of crank 137 and a wheel 149 is rotatably mounted at the end of crank 138 on axles 151 and 152 respectively.

As pointed out above, and as shown in FIG. 4, the pins are carried up pin elevator G in a generally horizontal position while resting on cross rods 67 with the top of the pin pointed either to the left or to the right (as shown). Wheels 148 and 149 are both so positioned laterally that each will coincide with the path of travel of the thinnest portion of the neck of the pins when the pin is oriented with its head to the left (wheel 148) or to the right (wheel 149). The geometry of the pins is such that when one of wheels 148 or 149, coincides with the path of travel of the thinnest portion of the neck of the pin the other of wheels 148 or 149 will coincide with a portion of the body of the pin. The various parts of pin orienting mechanism 106 are so related to conveyor G and to each other that when the body portion of a pin passing upward on the elevator contacts one of wheels 148 or 149 it will raise that wheel a sufficient distance along its path of travel to cause the corresponding deflector pin piece 111 or 112 to swing to its outermost position, and the other of pin pieces 111 or 112 to assume its vertical position with stop 125 or 126 as the case may be in contact with bracket 109. Thus no matter which way the pin is oriented on the elevator G the passage of the pin up the elevator will erect the appropriate deflector pin 113 or 114 so that as the pin is pushed out of the elevator by forward extension 105 of rear wall 69 the neck of the pin at a point just below the base of the head portion of the pin will come into contact with either deflector pin 113 or deflector pin 114 while the base of the pin will clear the other or pins 113 or 114. This forces the pin to enter slide 107 with its base down. As soon as the pin swings around and as it slides down slide 107 the upper portion of the pin slips out of contact with the erected deflector pin.

Slide 107 is bent at such an angle that the pins will slide down the slide readily. It is provided with upstanding side walls 153 and 154 of sufficient height to prevent the pins from jumping out. The upper end of the slide 107 is in such position as to receive the pin as it falls out of the pin elevator, and the lower end is in such position as to dump the pin directly onto pin conveyor I. The upper or receiving portion of slide 107 is wide enough to receive a pin oriented horizontally. The width of the slide decreases towards its lower end so that the bottom or exit portion is narrow enough that it will not pass a pin unless the pin is generally oriented in an up and down direction relative to the slide. As explained above, the action of pin orientor 106 causes the pins to enter slide 107 with their base first so that it is the base of the pin that comes into contact with conveyor I first, and the pin therefore is necessarily carried up conveyor I with its base forward. Since, as will be explained later, a common drive is provided for elevator G and conveyor I no more than one pin at a time can be delivered to conveyor I. The pins, therefore, proceed up conveyor I in a single file base first.

The primary advantages of elevator G and pin orientor 106 lie in the fact that both are simple, direct and fool-proof. There is no possibility that they can jam, that the parts can become bent, or the like. The elevator accepts pins one at a time but only if the pin is oriented parallel to cross rods 67. If a second pin tries to rise in a single position, or if the pin is not properly oriented, the second pin or the improperly oriented pin, falls out of the elevator. As the pin rides up elevator G past wheels 148 or 149 of pin orientor 106 the pin either clears these wheels or it doesn't. If it does not the upward motion of the pin pushes one wheel up and out of the way and this motion of that wheel erects the proper orienting pin and the linkage of orientor 106 forces the other wheel to the lower or intercepting position. The pin is forced out of the elevator merely by being urged into an unbalanced condition, and in falling necessarily passes through the upstanding portion of pin orientor 106. Under such circumstances the base is free to fall and the top is delayed. Even while the top is delayed the base falls right onto

slide 107 and the pin slides through slide 107 base first onto conveyor I solely under the force of gravity.

An identical pin orienting mechanism 155 and a similar slide 156 is provided at an appropriate lower level of elevator G for the purpose of orienting king pins Pk and delivering such king pins base first to king pin conveyor H. Pin orienting mechanism 155 and slide 156 are supported by bracket 157 which is mounted on the side walls 91 and 92 of elevator G.

King pin detector and deflector 158

As mentioned above, means are provided for detecting and removing king pins Pk from elevator G. These means which are indicated generally at 158 and consist of a pair of elements 159 and 160 inset into guides 75 and 76 of elevator G between rear wall 69 and the paths of conveyor drive chains 66 are shown in detail in FIGS. 8, 9 and 10.

Each element 159 and 160 consists of a king pin detector plate 162 and a king pin deflector plate 163 mounted in a common housing 164. Housing 164 is generally U-shaped with a rear wall portion 165, a side wall portion 166, and a front wall portion 167. Rear wall portion 165 is adapted to be mounted in rear wall 69, front wall portion 167 extends inwardly for a sufficient distance as to serve as a continuation of guide 75 or 76 as the case may be.

King pin detector plate 162 is pivotally mounted at its bottom end on support shaft 168 which in turn is mounted between front wall 167 and rear wall 165 near the lower end of element 158 or 159 in such manner that the free end of plate 162 is free to move toward and away from side wall 166. King pin deflector plate 163 is similarly mounted on support shaft 169 which is mounted between front wall 167 and rear wall 165 of element 158 or 159 near its upper end. Detector plate 162 is connected to deflector plate 163 by a linkage which includes bracket 171 mounted on the rear of plate 162, a shaft 172 pivotally mounted on bracket 173 which in turn is mounted on the inner side of side wall 166, bracket 174 mounted on the rear of plate 163, swinging link 175 which joins bracket 171 with one end of shaft 172 and swinging link 176 which joins the other end of shaft 172 with bracket 174. A compression spring 177 of substantial strength mounted between the rear of plate 162 and the inner portion of side wall 166 tends to normally urge plate 162 away from side wall 166. The action of the linkage is such that if plate 162 is pushed toward side wall 166, plate 163 is forced outwardly from side wall 166. By locating bracket 173 in an appropriate position relative to the ends of shaft 172 the magnitude of the relative motion of the two plates can be suitably regulated. For example, as shown, bracket 173 is closer to the bottom end of shaft 172 than it is to the upper end, thus magnifying the response of plate 162 to any motion of plate 163.

The free end of the king pin deflector plate 163 is formed on a taper with the intersection between the free edge and the rear side in an acute angle. An abutting portion 178 depending inwardly from the free edge is provided and acts as a contacting surface against the pins when deflector pin 163 is extended. The free edge of detector plate 162 is also tapered, but with an acute angle at the intersection between the free edge of the front side so that there is no interference between the two plates and the king pin will remain in contact with the detector plate 162 until the pin has been removed from the conveyor.

A stop is provided conveniently by having bracket 174 contact shaft 172 so that in the normal position deflector plate 163 is oriented parallel to side wall 166. Detector plate 162 is so shaped and the linkage is so arranged that its free end is parallel to, and in the same plane as deflector plate 163, when the deflector plate is in its normal position. The lower portion of detector plate 162 (that portion adjacent pivot 168) slopes towards the side wall

166 with its lower or pivot edge within the limits of front wall 167.

The elements 159 and 160 of king pin separator 158 are dimensioned and located as follows: The outer edge of front wall 167 is in the same vertical plane as the outer edge of front wall 167 is in the same vertical plane as the outer edge of guides 75 and 76 and serves as a continuation thereof. Guides 75 and 76 are separated by a distance substantially equal to the overall length of a king pin Pk. The plane of deflector plate 163 and of the free end of detector plate 162 is parallel to the plane of the inner edges of guides 75 and 76, but the horizontal distance between these elements in the normal position is substantially equal to the overall length of a common pin Pk. When a common pin Pk passes up the conveyor it will contact sloped surface of detector plate 162 of either element 159 or 160 (unless it is perfectly centered in the conveyor) and will be pushed laterally until it becomes centered in the conveyor G at which point it will pass right through king pin separator 158. Thus king pin separator 158 serves as a centering device for common pins Pk assuring that they will be in the proper position laterally for contact with pin orienting means 106.

When a king pin Pk comes up the elevator G it will, since its length is substantially equal to the distance between the inner edge of front wall 167 of both elements 159 and 160, press against the sloping lower portions of detector plate 162, forcing that plate on both elements toward side wall 166 against the pressure of spring 177 then will, through the linkage including shaft 172, force deflector plate 163 into its extended position. The king pin Pk will then contact the side of abutment 178 which depends from deflector plate 163 on both elements and will be forced forward relative to elevator G to the extent that its center of gravity is forward of the horizontal cross rod 67 supporting it. As soon as this happens king pin Pk will fall out of the elevator through king pin orienting means 155 onto king pin slide 156, and then in a base down orientation due to the action of king pin orienting mechanism 155 onto king pin conveyor H. The relative positions of the various parts of king pin detector and separator 158 as the king pin Pk is passing through is shown in FIG. 8.

Common pin conveyor I

Common pin conveyor I (see FIGS. 1, 4 and 5) comprises a conveyor belt 181 preferably a rubber belt with upstanding transverse ribs provided with a surface thereof, which passes around rollers 182 and 183. Belt 181 is of a suitable width to carry common pins Pk with the axis of the common pins parallel to the path of travel of the belt and is provided with side rails 184 and 185 to prevent the pins from falling off. Suitable framing and support means indicated at 186 and 190 are provided. Conveyor I extends between a position below the delivery end of common pin slide 107 and curved delivery slide 187, positioned to cooperate with common pin distributor J, and to deliver common pins to the pin receiving holders 283 provided thereon.

Common pin conveyor I is driven from a pulley 188 provided on the outward shaft of reduction gear 99, by means of transmission belt 189 which passes over a pair of idler pulleys 191, 192 mounted on a bracket 193 which is supported on framing member 190 and around a pulley provided on the shaft supporting roller 182. Since pin elevator G and pin conveyor I have a common drive both operate simultaneously.

King pin conveyor H

A similar conveyor H is provided to transport king pins Pk from the delivery end of king pin slide 156 to curved delivery slide 194 positioned to deposit king pins Pk in the king pin position of pin storage rack K. King pin conveyor H consists of two segments, a feed or first section 195, and a delivery or second section 196 which

are driven separately. Both sections comprise a conveyor belt 197, 198 respectively which preferably is a transversely ribbed rubber belt. Each said belt passes around a pair of pulleys which are indicated at 201, 202, 5 203 and 204. Both sections of the conveyor are supported in a frame indicated by brace 205 and framing member 206. Continuous side rails 207 and 208 supported on framing member 206 are provided to prevent the pins from falling from the conveyor.

- 10 The first section 195 of conveyor H is driven from conveyor I by means of a pulley 209 affixed to the shaft supporting roller 182. A drive belt 211 and a pulley 212 are fixed to the drive shaft 210 supporting roller 201. The second section 196 of conveyor H is driven from the 15 drive for pin sweep mechanism D which is indicated in FIG. 1 by motor 213 by means of a drive belt 214 passing around a pulley provided on drive shaft 215 of pin sweep mechanism D and pulley 216 fastened to the drive shaft 217 of roller 203 (see FIG. 1).
- 20 The drive control mechanism for king pin conveyor H is shown in detail in FIGS. 11, 12 and 13. The principal elements comprise a one revolution clutch on shaft 210 as indicated by base 218 and cam 219, a one revolution clutch on shaft 217 as indicated by base 221 and cam 222 and king pin sensing fingers 223. The one revolution clutch on shaft 210 serves to interrupt the drive between pulley 212 and roller 201 and the one revolution clutch on shaft 217 serves to interrupt the drive between pulley 216 and roller 203. King pin sensing fingers 223 are pivotally mounted on shaft 224 which is supported by a bracket 225 which in turn is supported by framing member 205. Sensing fingers 223 extend through slots provided in framing member 205 on each side of belts 198 inside of rails 207 and 208 in a position to be contacted by king pins Pk traveling on the conveyor. An L-shaped cam engaging lever 226 pivoted at 227 to bracket 228 is provided to engage cam 219. A similar L-shaped cam engaging lever 229 pivoted at 231 to bracket 232 is provided to engage cam 222.
- 30 Cam engaging lever 226 is actuated by rod 233 which passes through a hole provided in the free end of lever 226. Rod 233 is provided with a fixed washer 234 adapted to engage lever 236 on one side and with a light coil spring 235 retained by washer 236 adapted to engage the other side of lever 226, and when compressed to return lever 226 to a cam engaging position. The other end of rod 233 is pivotally attached at 237 to a mid portion of the upper end of crank arm 238 which in turn is pivotally mounted at 239 on bracket 232. Length adjusting means 241 are provided for rod 233.
- 40 To the lower end of crank arm 238 is pivotally attached at 242 a shaft 243 which passes through a hole in one arm of L-shaped lever 244 which is pivotally mounted at 245 on bracket 232 in such a position that the end of the 45 other arm of lever 244 interacts with the lever of the free arm of L-shaped lever 229. A fixed washer 246 is provided on shaft 243 on one side of lever 244 and a light coil spring 247 held in place by washer 248 is provided on the other.
- 50 The upper end of crank arm 238 is pivotally engaged at 249 to one end of shaft 251. Shaft 251 is pivotally engaged at its other end at 252 to crank arm 253 which is mounted in an upwardly extending position on shaft 224. Adjusting means 254 are provided in shaft 251 to 55 adjust its length. A light coil spring 255 is attached between pivot 252 at some convenient position below to keep the linkage under a slight degree of tension. A second crank arm 256 is attached to shaft 224 in a downward position. Crank arm 256 is adapted to be contacted by knob 257 mounted on the side of chain 258 as knob 257 passes around the upper side of sprocket 259. The other end of chain 258 passes around sprocket 261 which is mounted on shaft 262. A second sprocket 263 mounted on shaft 262 is positioned to engage rack 70 264 of pinsetting mechanism L and to be driven by the 75

motion thereof. It will be remembered from the general description above that pinsetting mechanism L descends to two different heights. One of these positions is adjacent the alley when the pins are being set and the other is somewhat removed from the alley when the machine is going through the deadwood cycle. Knob 257 is so located on chain 258 and the ratio of sprocket 261 to sprocket 263 is such that knob 257 engages crank 256 as shown in FIG. 12 only when mechanism L approaches the alley floor during a setting cycle, and does not contact crank 256 at all when mechanism L is in a deadwood cycle.

The remaining parts of the king pin conveyor drive mechanism are a push-arm 265 adapted to engage the rear side of the free arm of lever 229 and a spring loaded-power mechanism 266 adapted to engage the upper portion of crank arm 238 when crank arm 238 is in its forward position. Arm 265 is actuated by the mechanism that releases pins from common pin distributor J to pin storage rack K in a manner to be explained below, and when actuated is pressed against the free arm of lever 229 sufficiently to disengage lever 229 from cam 222. Spring mechanism 266 comprises washer 267, rod 268, brackets 269 which is attached to bracket 271 and spring 272 mounted over rod 268 between washer 267 and bracket 269. The forward travel of washer 267 is limited so that spring mechanism 266 comes into contact with the upper portion of crank arm 238 only when shaft 251 is pushed toward elevator G.

The sequence of operation of the king pin conveyor drive mechanism is shown in FIGS. 11, 12 and 13. The normal position of the mechanism is with lever 226 in contact with cam 219, with lever 229 in contact with cam 222, and with the pin sensing fingers 223 in the position shown in FIG. 11. In this condition there will be one pin on the second section 196 of conveyor H, and at least one pin on the first section 195 of conveyor H, and belts 197 and 198 will be motionless due to the action of clutches 218 and 221. This condition continues until the machine calls for a king pin Pk to be delivered to pin storage rack K. When this happens the mechanism that releases common pins from common pin distributor J to pin storage rack K through a suitable linkage advances push rod 265 momentarily against the rear surface of the free arm of lever 229, thereby releasing lever 229 from cam 222. Even though the movement of rod 265 is only momentary its action is sufficient to push the free end of lever 229 beyond the end of the engaging arm of lever 244. When this happens lever 244 is free to rotate and does so under the force exerted by spring 247 so that the end of the engaging arm of lever 244 comes into contact with the back surface of the free arm of lever 229 preventing the reengagement of lever 229 with cam 222 until this portion of the drive control mechanism is recocked.

FIG. 11 shows the drive mechanism at the moment that lever 229 is disengaged from cam 222 by the action of rod 265. Pulley 216 is engaged to roller 203 and thus belt 198 of second section 196 of conveyor H will, once lever 229 is disengaged from cam 222 move whenever sweep mechanism D is actuated. The motion imposed on belt 198 by one cycle of sweep mechanism D is more than sufficient to deliver the king pin Pk on the second section 196 of conveyor H to the king pin position in pin storage rack K. As this pin passes over fingers 223 fingers 223 are forced toward the left (as shown) out of the way. Since lever 244 is disengaged from the end of lever 229 lever 244 is free to slide along the rear surface of the free arm of lever 229 when fingers 223 are depressed, and the action of fingers 223 is opposed only by the light pressure exerted by springs 225 and 235. As soon as the pin Pk clears fingers 223, fingers 223 return to the position shown in FIG. 11 under the force exerted by these springs. In the meantime lever 226 remains in contact with cam 219 and therefore the first section 195 of conveyor H is dis-

engaged from its power source and no further pin can be delivered to the second section 196.

In the normal sequence of operation of the machine, all of the pins stored in pin storage rack K are dumped onto pinsetting mechanism L as pinsetting mechanism L begins its pin setting cycle (the setting cycle is always preceded by a pin sweep cycle so that if a king pin is called for such a pin will be delivered to rack K prior to the pin setting cycle). Also since the pins stored in pin storage rack K are all dumped into pinsetting mechanism L as pinsetting mechanism L begins its pin setting cycle storage rack K is always clear of pins, and ready to receive a king pin (if called for) as soon as the pinsetting mechanism L goes through its setting cycle.

As pinsetting mechanism L reaches the bottom of its stroke in the pin setting cycle knob 257 mounted on chain 258 contacts crank arm 256 as shown in FIG. 12. (FIG. 12 shows limit of the stroke at the instant mechanism L reverses its direction.) As knob 257 contacts crank 256 it pushes crank 256 toward the left and fingers 223 toward the right. This pushes rod 251 toward the right which in sequence releases lever 226 from cam 219 thus connecting first section 195 of conveyor H with its drive means pin elevator G. This action also depresses lever 244 out of the contact with lever 229 so that lever 229 will return to the surface of cam 222 and reengage with the stop provided thereon during the next rotation of pulley 216 thereby disengaging second section 196 of conveyor H from its drive means.

As pinsetting mechanism L returns towards its raised position knob 257 moves out of contact with crank 256 and spring mechanism 266 acting on crank 238 returns the mechanism to the condition shown in FIG. 13 where as explained above, the second section 196 is disengaged from its drive means, where the first section 195 is engaged with its drive means. The frictional drag of the motion of belt 197 against the king pin Pk already on belt 197 will advance this king pin Pk part way onto stationary belt 198, the resting position being determined by a balance between the frictional drag of moving belt 197 and the frictional drag of stationary belt 198 acting against the king pin in question. In its resting position a king pin would be carried forward by belt 198 should belt 198 be actuated. However, normally more than one king pin is present on conveyor H (the machine being provided with a total of three). Under these conditions the base of the second king pin Pk on belt 197 would be pushed against the top of the first king pin and advance the first king pin across the surface of stationary belt 198 until the base of the first said king pin hits against fingers 223. Fingers 223 are so located that they would be pushed to the position shown in FIG. 11 by a single king pin on the second section 196 before a second king pin can come into contact with belt 198. As soon as the king pin Pk on belt 198 has been pushed far enough forward to push fingers 223 into position shown in FIG. 11 the movement of fingers 223 toward the left pulls rod 233 toward the left thereby reengaging lever 226 with cam 219 and disengaging the drive for belt 197 of the first section 195 of conveyor H. The bottom edge of crank arm 256 is bevelled so that knob 257 in this position will clear crank arm 256. This prevents starting belt 197 in the event the pins are set in a combination not including a king pin, and a king pin remains on belt 198. The first section 195 of conveyor H is long enough to accommodate a single king pin with a second king pin partially on section 195 and partially on slide 156. This gives king pin conveyor a capacity of three king pins (one on the second section 196 and two on the first section 195) so that all of the king pins normally used in the machine may be so accommodated in the event that a particular game does not require king pins. As soon as fingers 223 reach the position shown in FIG. 11, conveyor H becomes inoperative until such time as push rod 265 is activated and the cycle starts all over again.

The pin resetting portion of the pinsetting machine is built around a stationary element comprising a pin storage rack K which consists of bottom plate 274, common pin storage tubes 275 and top plate 276. Bottom plate 274 is mounted at its sides on the side walls C of alley A.

As shown in FIG. 14 common pin distributor J comprises a circular plate 281 mounted parallel and above top plate 276 of pin storage rack K, and adapted to rotate about its axis on a suitable bracket indicated at 282. Around the periphery of circular plate 281 there are provided on a common radius a number of equally spaced pin receiving and holding brackets indicated generally at 283. A number of such brackets 283 equal to the number of pins to be distributed (eight in this instance) are provided. Around the edge of circular plate 281 there are also provided a plurality of equally spaced slots 284 inset into the periphery of plate 281. The number of slots 284 so provided is equal to twice the number of pin receiving and holding brackets 283 (sixteen where there are eight such brackets). Slots 284 are conveniently located relative to brackets 283 so that one such bracket is placed between each second pair of slots 284. Plate 281 is driven rotationally and indexed by pawls 285 which extend upwardly from horizontal drive chain 286 of indexing drive mechanism indicated generally at 287 which pawls engage in successive slots 284 about the periphery of plate 281. As will be explained later, a full rotation of chain 286 moves plate 281 a distance equal to the distance between successive brackets 283 bringing such successive brackets 283 into position to receive pins from slide 187 at the end of the conveyor I. A half rotation brings each of brackets 283 directly above the upper end of the corresponding pin storage tubes 275 and pin storage rack K (said upper end of tubes 275 being of the same number equally spaced and at the same center line radius as the pin receiving portions of brackets 283).

Each pin receiving and holding bracket 283 as shown in FIG. 15 consists of a base 288, an upstanding pin receiving holder 289 mounted on base 288 with its bottom portion extending therethrough and pin release mechanism 291 mounted on base 288. Base 288 is fastened to plate 281 and is located with the pin receiving holder 289 thereof located over a suitable aperture provided in plate 281.

Upstanding pin receiving holder 289 consists of a circular base portion 292 having an inside diameter slightly greater than the diameter of a pin, and an upstanding semi-circular shield portion 293. Brackets 283 are so located on plate 281 that when each bracket is in the pin receiving position the top of base portion 292 of bracket 283 is located directly below the exit portion of slide 187 of conveyor I as indicated in phantom in FIG. 15 (where the dotted line indicates the cross section of conveyor 187 at its center line). Shield portion 293 acts as a deflector plate for common pins Pc coming over slide 187 and directs such pins into the pocket formed by circular base portion 292. It will be noted that shield portion 293 is canted somewhat relative to the radius of plate 281 (and to the axis of base 288 of bracket 283). The reason for this is that since the nine pin target is symmetrical with the center line of the alley, it is most convenient to have the dump position of distributor J (the position where the pins held in brackets 283 are directly above the upper end of pin storage tubes 275) also symmetrical with the center line. Since brackets 283 (there being eight) are located with their longitudinal axis along radii at 45° intervals around plate 281, and since the pin receiving position is a half cycle or 22½° the exit end of slide 187 of conveyor I is offset 22½° from the center line and is generally parallel thereto. The shield portion 293 is located and rotated a corresponding amount so that a pin coming over slide 187 will strike the shield at a point half way between the two edges thereof. The edge of the shield closest to

the periphery of plate 281 is of course inset sufficiently to create slide 187 as plate 281 rotates.

A horizontal slot 294 is provided in the front edge of base portion 292 to permit pin sensing crank 399 and pin detecting switch 415 mounted on top plate 276 of storage rack K to extend into base portion 292 sufficiently to be deflected by the presence of or entry of a pin in bracket 283 (but not sufficiently to interfere with the entry of such a pin). The rear portion of base portion 292 is provided with a vertical slot 295 of sufficient size to permit entry of pin holding latch 296 of pin release mechanism 291. A brace 297 is provided to support pin holder 289.

Pin holding latch 296 of pin release mechanism 291 has an upstanding portion adapted when in its forward position to enter slot 295 where it contacts pins Pc in holder 289 and prevents the exit of such pins therethrough. The rearwardly extending horizontal portion of latch 296 is provided with a pair of laterally spaced laterally extending slots, and latch 296 is mounted for reciprocal travel between two nylon washers on each of two bolts 298 and 299. Bolts 298 and 299 each pass through one of the two slots and are fastened to base 288. Release mechanism 291 is actuated by a linkage which comprises two crank arms 301 and 302 pivotally connected to each other at 303. Crank arm 301 is pivotally connected at its upper end to mounting post 304 which is upstandingly connected to the top surface of the rearwardly extending portion of latch 296. Arm 302 is fixedly connected at its other end to shaft 305 which passes through upstanding mounting post 306 provided on the top surface of base 292 near the rearward edge thereof. Shaft 305 is adapted to rotate relative to post 306. An abutting post 307 is upstandingly mounted on the top surface of base 292 and is adapted to contact the side of arm 301 or arm 302 in the vicinity of pivot 303 when arms 301 and 302 are just past dead center. A spring 308 mounted between pivot 303 and base 292 is provided to normally urge pivot 303 into contact with post 307.

Shaft 305 extends through base 292 to a position below the bottom surface of plate 281. Two actuating cranks 309 and 311 affixed to shaft 305 are provided to actuate release mechanism 291. One of these cranks, crank 309, is affixed to shaft 305 between arm 301 and the top of post 306 and extends in a generally lateral direction outwardly of bracket 283. The other of said cranks, crank 311, is located below base 292 and extends inwardly generally along the axis of bracket 283. When either arm is moved counterclockwise crank arm 301 is likewise moved counter-clockwise thus moving pivot 303 away from abutting post 307 across the dead center position and retracting latch 296 permitting the pin Pc retained in holder 289 to be released. As soon as the forces tending to move crank arm 309 or 311 are released spring 308 returns pivot 308 to a position contacting abutting post 307 which returns latch 296 to its forward position and arms 301 and 302 to a position beyond the dead center point wherein any force tending to force latch 296 rearwardly is exerted against abutting post 307. This prevents any movement of latch 296 in a rearward direction.

Pin dump mechanisms 312 and 313

It will be remembered that there are two separate pinsetting sequences to be performed by the machine. There is an automatic pinsetting sequence where all of the nine pins are placed on the alley during each pinsetting cycle, and a pin selector sequence where only those pins selected by the bowler are so placed during any such cycle. Lower actuating arm 311 is adapted to be actuated by a mechanism indicated generally at 312, and which is designed to release the pins retained in each of pin holding brackets 283 simultaneously into pin storage 275 of pin storage rack K. Upper actuating arm 309 is adapted to be activated by a mechanism indicated generally at 313 and which is designed to release only those pins selected

by the bowler from brackets 283 into storage tubes 275 of rack K.

Selective pin release mechanism 313 comprises a housing 314 mounted above plate 281 on a mounting bracket 315 which extends internally of bracket 282 and is secured to top plate 276 of storage rack K. Housing 314 which is stationary supports a plurality of solenoid units 316 equal in number to the number of pin receiving and holding brackets 283 which are mounted on circular plate 281 (eight in this instance). Each solenoid unit 316 is provided with a plunger 317 which is adapted to extend when the solenoid is actuated and to bear against the rear of release actuating crank 309 of the adjacent bracket 283 thus releasing the pin Pc retained in said bracket. Solenoid 316 is so located that crank 309 of each bracket 283 is in a cooperating position with each plunger 317 when distributor J is in its half cycle or dump position with the pins Pc and holders 289 directly above the entrances to tubes 275 of bracket K. Each solenoid 316 is separately connected to a pin selector switch (not shown) or preferably to a holding relay which in turn is actuated by a pin selector switch by appropriate wiring. A separate pin selector switch is provided at the bowler's position for each of the pins so that the bowler may select the desired pins at random. It is convenient to provide a holding relay in each circuit, which relay is actuated by the pin selector switch, a selection cancelling switch to release the relays in case there is an error or in case the bowler changes his mind, and a pin release switch which may also serve as a pin setting switch to release the selected pins from the distributor J into rack K by actuating the appropriate solenoids 316 through the holding relays. Suitable means are also provided to prevent the actuation of solenoids 316 until distributor J is full of pins and in its half cycle or dump position, or when individual pin selection is not called for in the game being bowled.

The automatic pin release mechanism 312 includes a circular plate 318 mounted for limited rotational travel relative to plate 281 horizontal to plate 281 on mounting bracket 282. On the top surface of dump plate 318 are mounted a plurality of horizontal rollers 319 each adapted to engage one of the actuating cranks 311 of brackets 283. After all of the pin receiving and holding brackets 283 have received the pins Pc, and as plate 281 comes into the half cycle or dump position, dump plate 318 is retarded as plate 281 rotates bringing each of rollers 319 into contact with its corresponding crank 311 and moving each said crank 311 in a counter-clockwise direction, thereby releasing all of the pins from distributor J into storage rack K simultaneously. The mechanism for doing this is shown in FIG. 16.

As shown in FIG. 16 the dump arm 321 is pivotally mounted on shaft 322 which in turn is mounted on a bracket 323 attached to the lower side of plate 281. Dump arm 321 extends inwardly from shaft 322 substantially parallel to plate 281. An abutting stop 324 is mounted on bracket 323 to limit the rotation of arm 321 in a direction toward the direction of plate 281. A strong coil spring 325 normally urges dump arm 321 against stop 324. Top portion of dump arm 321 is approximately the same level as dump plate 318 and terminates just short of the outer periphery of plate 318. A link 326 pivoted at one end to the top of arm 321 and at the other end to the top of plate 318 is provided. Link 326 is of substantial length and is oriented at substantially right angles to the direction of dump arm 321. The outer portion of dump arm 321 is provided with an extension 327 which extends below dump plate 318 in the space between the bottom of plate 318 and the top of top plate 276 of storage rack K.

Dump arm 321 since it is mounted on rotating plate 281 moves with plate 281. Dump arm extension 327 in its travel is adapted to come into contact with horizontal roller 328 of dump trip mechanism 329 mounted on plate

5 276. When dump roller 328 is in position to contact dump arm extension 327 as dump arm 321 passes by dump roller 328 presses against the side of dump arm 321 causing dump arm 321 to rotate in a clockwise direction against the pressure of spring 325. This movement of arm 321 through link 326 causes dump plate 318 to stop momentarily (move counterclockwise relative to plate 281) while plate 281 continues to move. This forces dump plate rollers 319 against actuating crank 311 of pin holding brackets 283, releasing the pins Pc from distributor J into pin storage rack K. As soon as plate 281 rotates sufficiently to permit the end of extension 327 of dump arm 321 to clear roller 328 of dump trip mechanism 329, spring 325 returns dump arm 321 into its normal position against stop 324, and this movement acting through link 326 returns dump plate 318 to its normal position. Dump trip mechanism 329 is so located relative to dump arm 321 that roller 328 contacts arm 321 only when all of the brackets 283 contain pins and the common pin distributor J is in its dump position (as shown in FIG. 14).

20 Horizontal roller 328 of dump trip mechanism 329 is rotatably mounted on shaft 331 which is in turn mounted on one end of rocker arm 332. Rocker arm 332 which is substantially right angled is pivotally mounted at its bent point to bracket 333 which is mounted on the underside of plate 276. An aperture 334 is provided in plate 276 to permit passage of roller 328 into the plane of dump arm 321. The downwardly extending arm of rocker arm 332 is connected to plunger 334 of solenoid 335 mounted on bracket 336 attached to the underside of plate 276. A compression spring 337 is provided between bracket 336 and rocker arm 332 to urge roller 328 into the raised and intercepting position except when solenoid 335 is actuated. Plunger 334 of solenoid 335 is drawn toward solenoid 335 when solenoid 335 is actuated. An adjusting screw 338 is provided mounted on the horizontal arm of rocker arm 332 and it cooperates with the bottom surface of plate 276.

40 Dump trip mechanism 329 reciprocates between the position shown in dotted lines and the position shown in phantom in FIG. 16. In the solid line position roller 328 is in a position to contact dump arm 321. Solenoid 335 is actuated as mechanism 329 assumes the position shown in phantom and roller 328 is withdrawn out of contacting position with dump arm 321. Solenoid 335 is actuated only when the game called for by the bowler requires individual pin selection.

45 Since the motion of dump trip mechanism 329 in response to the action of solenoid 335 is the only signal to pin distributor J differentiating between an automatic pin release sequence and a selective pin release sequence, the position of rocker arm 332 is transmitted to indexing drive mechanism 287 by means of rod 339 mounted between the lower vertical portion of rocker arm 332 and time delay lockout rocker arm 341 pivotally mounted on pivot post 379 of index drive mechanism 287. Rod 339 is provided with length adjusting means indicated at 342. To prevent excessive force from being exerted on rocker arm 341 when rod 339 is drawn toward dump trip mechanism 329 rod 339 extends through a hole provided in rocker arm 341 and exerts pressure on the rear side thereof through spring 343 mounted over rod 339 between the rear side of arm 341 and a nut 344 mounted at the end of rod 339.

Indexing drive mechanism 287

50 Indexing drive mechanism 287 (FIGS. 17 and 18) is mounted alongside and below circular plate 281 of common pin distributor J (in the general location indicated in FIG. 14) by means of brackets 351 and 352 which are attached to top plate 276 of pin storage rack K. As mentioned above upstanding pawls 285 mounted on drive chain 286 are adapted to engage in slot 284 provided about the periphery of circular plate 281. Chain 286 passes around drive sprocket 353, identical idler sprocket

354 and slack adjusting idler sprocket 355. Sprockets 353 and 354 are rotatably mounted on the top surface of frame member 356 of drive mechanism 287 and slack adjusting idler sprocket 355 is mounted on plate 357 slidably mounted on frame member 356 on shafts 358, 359 and 360 respectively.

Sprocket 353 is driven by means of a gear train comprising gear 362 mounted on shaft 358, idler gear 363 and drive gear 364 mounted on output shaft 365 of reduction gear 366. Reduction gear 366 is driven by sprocket 367 mounted on input shaft 368 which is connected by drive chain 369 to output sprocket 370 on output shaft 371 of motor 372. Reduction gear 366 and motor 372 are both mounted on frame 373 which are supported by frame member 356.

Drive gear 364 is fastened to shaft 365 by means of a single revolution clutch (drive clutch) 377 located as shown between reduction gear 366 and drive gear 364. A second one revolution clutch (time delay clutch) 378 is provided on shaft 365 above gear 364 as shown. Shaft 365 rotates in a counter-clockwise direction. The gearing is such that one revolution of gear 364 drives chain 286 through exactly one complete cycle moving rotatable plate 281 one full station. Likewise a half rotation of gear 364 drives chain 286 through exactly one-half of one cycle (i.e. moves plate 281 from the pin receiving position to the dump position). Pawls 285 are equally spaced along chain 286 and sprockets 353 and 354 are so located and so spaced that at least one of pawls 285 is engaged in at least one of plates 284 at all times. Motor 372 and hence reduction gear output shaft 365 runs continuously while the machine is in operation.

A pair of pivot posts 379 and 381 are mounted on frame 382 which frame is fastened to the top of reduction gear 366. Posts 379 and 381 are both carefully located on either side of shaft 365 with their axes parallel to the axis of shaft 365 at equal distances from the axis of shaft 365 along the line that passes through the axis of both posts and of said shaft. As shown in FIGS. 17 and 18 post 379 is to the right of shaft 365 and slightly to the rear while post 381 correspondingly is on the left and slightly toward the front. The various cam engaging arms employed in controlling the index drive mechanism are pivotally attached to one or the other of posts 379 and 381.

Drive clutch 377 is provided with a single spiral cam element 383 having a perpendicular abutting surface 384 adapted to engage a stop arm thereby disengaging clutch 377 from shaft 365. Drive wheel 364 is connected to shaft 365 through clutch 377 so that drive wheel 364 rotates with shaft 365 only when clutch 377 is free to rotate.

Time delay clutch 378 is provided with two identical interconnected spiral cams 385 and 386, each of which has a perpendicular butting surface 387 and 388 respectively. Surfaces 387 and 388 are separated by 180°. Clutch 378 is also provided with a cam 389 which cam has a segment having a substantially increased radius forming a projection 391. Stop arms are provided to engage in abutting surfaces 387 and 388. When cams 385 and 386 are both released, cam 389 is free to rotate with shaft 365.

In normal operation abutting surface 384 of cam 383 of drive clutch 377 is engaged by arm 392 (see FIG. 19 for details) which is one portion of rocker arm assembly 393 pivotally mounted on pivot post 379. The other arm of rocker arm assembly 393 extends inwardly and is attached to push rod 394 which extends laterally and terminates in the lower portion of vertical rocker plate 395 which is pivotally attached at 396 near its mid-point to frame member 356. A second rocker arm 397 which is attached at one end to the upper arm of rocker plate 395 extends laterally and is pivotally attached at 398 to pin sensing crank 399. Pin sensing crank 399 is pivotally mounted on top plate 276 at 401. Rod 394 is provided with length adjusting means 402, and 403. A spring 404

and a stop 405 are provided between the lower portion of rocker plate 395 and frame 373.

As mentioned above, pin sensing crank 399 extends into horizontal slot 294 provided in the front outer edge 5 of base portion 292 of each of the upstanding pin receiving brackets 283, which are mounted on plate 281 of common pin distributor J. When a blowling pin P enters holder 289 crank 399 is displaced as indicated in dotted lines in FIG. 19. This moves rod 397 toward the right which tilts rocker plate 395 pushing rod 394 toward the left as indicated. This action pushes stop on 392 out of contact with abutment 384 of cam 383 thereby releasing drive clutch 377 and permitting drive gear 364 to rotate. This activates drive chain 286 moving pawls 285 and moving plate 281 of distributor J. As soon as the particular pin receiving bracket 287 moves clear of crank 399, crank 399 is returned to its normal position by the force exerted by spring 404 on the linkage and cam engaging arm 392 is returned to a position to reengage abutting 10 surface 384 of cam 383 and to disengage clutch 377 after cam 383 and therefore drive gear 364 has made exactly one revolution. As mentioned above, one revolution of gear 364 drives plate 281 one full station so that when cam engaging arm 392 disengages drive clutch 377 and 15 thereby stops the rotation of plate 281 the next succeeding pin receiving bracket 283 is exactly in position under slide 187 of pin conveyor I. If this next pin receiving bracket 283 happens to contain a pin (as in selective bowling) pin sensing crank 399 is again displaced as this next succeeding bracket 283 comes into pin receiving position thereby 20 moving cam engaging arm 392 out of cam engaging position and permitting the drive to continue through another cycle moving the next succeeding pin receiving bracket 283 into pin receiving position. The index drive mechanism 25 is thereby controlled solely by the presence or absence of a pin in a pin receiving bracket 283. Pin distributor J will continue to move until an empty pin receiving bracket 283 comes under slide 187 of conveyor I. As soon as a pin enters this bracket distributor J will 30 begin to rotate and again continue to rotate until the next empty pin receiving bracket 283 comes under slide 187.

The remainder of the controls on index drive mechanism 287 relate to stopping the drive in the half cycle or 35 dump position where brackets 283 and plate 281 are directly above the entrances to pin storage tubes 275 of pin storage rack K. When the machine is in the automatic dump cycle the movement of plate 281 of distributor J is stopped only momentarily in order to permit the pins contained in distributor J to fall clear of plate 281 before the movement of the plate resumes. This prevents a pin from jamming between the top plate 274 of storage rack K and plate 281 of pin distributor J. In selective bowling on the other hand plate 281 is stopped in the dump 50 position and remains in that position until the selected pins have been released from pin distributor J.

Since index drive mechanism 287 is actuated by the presence of pins in brackets 283, and pins can be delivered to brackets 283 only when elevator G and common pin 55 conveyor I are operating, means associated with pin distributor J are provided to start and stop motor 97 which drives elevator G and conveyor I. These means include switch actuating cams 406, 407 and 408 mounted on the top surface of plate 281 near its outer periphery and associated switches 411 and 412 and 413 mounted on upper plate 276 of pin storage rack K. Each switch actuating cam is mounted at a different elevation so that it will contact only one of switches 411, 412 and 413. Switches 411, 412 and 413 are conventional micro switches shown 60 diagrammatically in FIG. 14.

Cam 406 actuates associated switch 411 when the bracket 283 corresponding to the seventh pin position is lined up with slide 187 on pin conveyor I. The term seventh pin position refers to the fact that the pins are released from pin distributor J only in a single orientation

of that distributor. This orientation is that corresponding to the position where in the automatic pin release sequence dump on 321 mounted on plate 281 contacts rollers 328 of dump trip mechanism 329 mounted on plate 276 of storage rack K. After the pins are dumped it is always the same pin receiving bracket 283 that next comes into position under slide 187 of common pin conveyor I. This bracket 283 for convenience is referred to as the first pin position. The succeeding brackets are similarly referred to as the second pin position, third pin position, etc. in the order in which these brackets come under slide 187. The eighth pin position represents the last bracket 283 to be filled before distributor J is completely full of pins and ready to be dumped.

The function of switch 411 is to disconnect the power supply to motor 97 and therefore stop elevator G and conveyor I if pin storage rack K contains pins. As explained above, this condition obtains unless pinsetting mechanism L has gone through a pinsetting cycle since the last time the pins were dumped from distributor J to rack K. Whether or not pinsetting mechanism L has gone through such a cycle is determined by a second switch (not shown) actuated when mechanism L has gone through a full cycle. Such a switch can conveniently be mounted on storage rack K in position to contact a switch actuating projection on rack 414 of pinsetting mechanism L when rack 414 goes through a full stroke. As soon as pinsetting mechanism L has gone through a full cycle (or if it has done so prior to distributor J reaching the seventh pin position) switch 411 is rendered inactive and the feed of pins to distributor J is continued.

Cam 407 contacts associated switch 412 just after the pin receiving bracket 283 associated with the eighth pin receiving position leaves delivery chute 187. Switch 412 shuts off motor 97 and stops conveyor I and elevator G during the dump cycle. Cam 408 contacts associated switch 413 as the pin receiving bracket 283 associated with the first pin position comes under chute 187 at the completion of the dump cycle and restores the power to pin elevator drive motor 97 thus restoring the supply of pins to distributor J.

When the machine is on a selective bowling cycle where individual pins are placed on the alley not all of the pins contained in distributor J will be released to storage rack K at any one time. Thus after the pins have been selectively released from distributor J there will always be some pins remaining in distributor J. As explained above, when a pin receiving bracket 283 containing a pin comes into pin receiving position under chute 187 the presence of the pin in this bracket is sensed by pin sensing crank 399 and the index drive 287 is released for another indexing cycle. There is the possibility that under these circumstances a pin will be delivered to pin delivery chute 187 while pin distributor J is in motion. To avoid this possibility a pin detecting switch 415 which comprises a laterally extending arm pivotally mounted on top plate 276 of rack K and which is adapted to extend laterally into slot 294 of bracket 283 is provided in a position to detect the presence of a pin in the next succeeding bracket 283 as distributor J begins to move after the next preceding bracket 283 has received a pin. Thus for example, if a pin remains in the second pin position the presence of this pin will be detected by pin detecting switch 415 as distributor J begins to move after a pin has been deposited into the first pin position. Switch 415 is a time relay switch and when actuated shuts down motor 97 of elevator G for a time equal to the length of time required for index drive 287 to complete two cycles thus preventing the delivery of pins while the distributor J is in motion. If switch 415 is repeatedly actuated as when a succession of pins are contained in successive brackets 283 the time delay is correspondingly increased so that motor 97 does not restart until an empty bracket 283 is in pin receiving position under chute 187.

A two step index drive actuating cam 417 is provided on the under side of plate 281 in position to contact cam follower 418 pivotally mounted on upstanding post 419 which is mounted on frame 356 of index drive 287. Cam follower 418 is provided with a cam follower roller 421 with a spring 422 mounted between arm 423 of follower 418 and frame 356 normally urging follower 418 to a cam contacting position. The details of the operation of the several positions of cam followers 418 are shown in top view in FIGS. 21, 22, 23 and 24 and in perspective view in corresponding FIGS. 25, 26, 27 and 28. In both views parts not involved in the operation have been omitted for clarity.

Arm 423 of follower 418 is mounted on a collar 424 which is pivotally mounted on shaft 419. Collar 424 is provided with two laterally extending projections 425 and 426. Projection 425 is adapted to contact one arm of rocker arm 427 which is pivotally mounted on post 381. The other arm of rocker arm 427 is adapted to engage abutment 388 of spiral cam 386 of time delay clutch 378. Projection 425 is so oriented that it does not contact rocker arm 427 except when rollers 421 of follower 418 is deflected laterally by the second stage of cam 417.

Projection 426 is adapted to engage one arm of rocker arm 428 which is supported by collar 429 pivotally mounted on post 381. The other arm of rocker arm 428 is adapted (when released) to engage abutting surface 384 of spiral cam 383 of drive clutch 377. A second horizontal arm 431 mounted on collar 429 is adapted (when released) to contact timer cam 389 of time delay clutch 378 and to be deflected by projection 391 thereon. Projection 426 is so oriented that arms 427 and 431 are held out of contact with their respective cams during the normal position of cam follower 418 but are released to contact the cam when follower 418 is deflected by the first and second steps of cam 417. Springs 432 and 433 are provided to urge arms 427 and 428 into contact with the corresponding cams.

The normal position of cam follower 418 is shown in FIGS. 21 and 25. In this position arm 427 is in contact with abutment 388 of cam 386 rendering timer clutch 378 inoperative. Similarly arm 428 is held out of contact with cam 383 of drive clutch 377. Thus each time pin sensing crank 399 is deflected cam 387 of clutch 377 is released by arm 392 momentarily and is free to make a complete rotation before again engaging arm 392 thus moving plate 281 of distributor J a full indexing cycle.

Cam 417 is so located on the underside of plate 281 that roller 421 of follower 418 is deflected by the first step of cam 417 when bracket 283 corresponding to the eighth pin position is in a pin receiving position under slide 187. This position is shown in FIGS. 22 and 26. When roller 421 of follower 418 engages the first step of cam 417 collar 424 is rotated sufficiently to move the projection 426 out of contact with rocker arm 428, but not far enough to move projection 425 into contact with rocker arm 427. Thus in this position rocker arm 428 is permitted to come into contact with cam 383 while time delay clutch 378 remains inoperative.

When a pin enters the bracket 283 corresponding to the eighth pin position cam 383 is released by arm 392 and abutting surface 384 of cam 383 rotates into contact with arm 428. The length of arm 428 is such that cam 383 rotates exactly one-half of one revolution when surface 384 contacts arm 428. This moves plate 281 of distributor J into the dump position, the position where the pins are released automatically if the machine is in an automatic pin release cycle. This movement of plate 281 brings cam follower 418 into contact with the second step of cam 417 as shown in FIGS. 23 and 27.

When in contact with the second step of cam 417 follower 418 rotates collar 424 sufficiently to move projection 425 into contact with rocker arm 427. This releases the other end of rocker arm 427 from abutting surface

388 of cam 286 of time delay clutch 378 permitting time delay clutch 378 to rotate. At this point arm 428 is still in contact with abutting surface 384 of cam 383 of drive clutch 377 holding the index drive motionless. After time delay clutch 378 makes almost one complete revolution projection 391 of cam 389 comes into contact with arm 431, deflecting arm 431 and thereby releasing arm 428 from contact with abutting surface 389 of cam 388. This is the condition shown in FIG. 28.

As soon as cam 388 is released drive clutch 377 is free to rotate which in turn permits drive gear 364 to rotate thereby advancing plate 281 of distributor J. As plate 281 rotates, cam follower 418 is released from cam 417 (the condition shown in FIG. 24) and returns to its normal position as shown in FIGS. 21 and 25. Arm 427 engages abutting surface 388 of cam 386 thus disengaging time delay clutch 378. Time delay clutch 378 remains disengaged until distributor J again returns to the dump position where follower 418 is in contact with the second step of cam 417. Abutting surface 384 of cam 383 of drive clutch 377 after rotating a half revolution again contacts arm 392 stopping plate 281 of distributor J in such position that bracket 283 corresponding to the first pin position is in a receiving position of the slide 187.

The action of time delay clutch 378 causes plate 281 of distributor J to pause long enough in the dump position to ensure that all the pins P_c are clear of plate 281 before the motion of plate 281 resumes.

When the pinsetting machine is in a pin selector sequence, plunger 334 of solenoid 335 is retracted as mentioned above (see FIG. 16). Through the linkage including push rod 339 this brings cam contacting arm 434 of time delay lockout rocker arm 341 into contact with abutting surface 387 of cam 385 of time delay clutch 378. Thus, so long as solenoid 335 is actuated clutch 378 is prevented from rotating even when cam follower 418 is on the second step of cam 417 and rocker arm 427 is released from abutting surface 388 of cam 386. This renders the mechanism involving timer cam 388, timer cam projection 389 and arm 431 inoperative to release rocker arm 428 from contact with abutting surface 384 of cam 383 of drive clutch 377. Thus when the machine is in a pin selecting sequence the index drive mechanism 287 moves pin distributor J into the dump position in the normal way, but at that point locks itself out. A secondary means is provided to release the index drive mechanism 287 after the pins have been dumped from distributor J into storage rack K under such circumstances. The secondary means comprises solenoid 435 with its associated solenoid plunger 436 which is pivotally attached to arm 437 mounted on collar 429 on the opposite side of collar 429 from arm 428.

As mentioned above, it is convenient to wire the machine so that in a pin selector sequence the pin selecting buttons provided at the bowler's position actuate holding relays which, on signal, are released actuating the individual pin dump solenoids 316 simultaneously. Such a signal is provided for example by the pin free set button located at the bowler's position. The signal that is used to release pins P_c from distributor J also actuates the solenoid 435 through a time delay switch which allows enough pause to permit the pins to clear plate 281 of distributor J. When actuated plunger 436 is retracted momentarily and pulls arm 428 out of contact with abutting surface 384 of cam 383 of drive clutch 377 permitting clutch 377 to rotate to the full cycle position where it is disengaged by arm 392, and where bracket 283 corresponding to the first pin position is in a pin receiving position under slide 187.

Projection 391 of timer cam 389 of time delay clutch 378 is also used to actuate push rod 265 (FIGS. 11, 12 and 13). Push rod 265 actuates the second section 196 of king pin conveyor H initiating the delivery of one king pin P_k to the king pin position in storage rack K as described above. Push rod 265 is pivotally connected

at one end to one arm of right angled crank 441 which is arranged laterally and pivoted at its bent point on shaft 442. Shaft 442 is arranged vertically on bracket 443 which depends from the side of motor bracket 373.

- 5 The other arm of crank 441 is pivotally connected to rod 444 which in turn is pivotally connected to outwardly and downwardly extending arm 445 of rocker arm 446 which is pivotally mounted on pivot shaft 379. Rocker arm 446 also includes a cam engaging arm 447 adapted to rest against timing cam 389 and to be displaced by projection 391 of cam 389 immediately before the position in which the projection 391 engages arm 431. Thus as cam 389 revolves arm 447 is displaced by projection 391. This motion which is transmitted through rocker arm 446 moves rod 444 to the left (as shown in FIGS. 17 and 18) displacing crank 441 and causing rod 265 to advance thereby releasing lever 229 from engagement with a cam 222 of clutch 221. In this way one king pin P_k is released every time the common pins P_c are dumped automatically from distributor J to pin storage rack K.

- 25 Since time delay clutch 278 is locked out during selective bowling sequences, the actuation of rod 265 by the rotation of cam 389 does not occur. A supplementary means is provided for the selective release of a king pin when the king pin is desired in a selective bowling sequence. The supplementary means comprises solenoid 448 mounted on bracket 443 with its plunger 449 engaging crank 441 at a point between rod 265 and pivot 442. This solenoid is wired in the same way as common pin release solenoid 316 and when actuated in response to the selection of a king pin by the bowler, plunger 449 retracts advancing rod 265 and releasing lever 229 from engagement with cam 222 of clutch 221.

35 Pin storage rack K

40 As mentioned above, pin storage rack K comprises an upper plate 276, a bottom plate 274 and a plurality of storage tubes 275 equal to the required number of common pins P_c extending therebetween. The length of each tube 275 is at least equal to the height of a common pin P_c so that such pins can be conveniently stored in rack K. The upper end of each tube 275 terminates in an aperture provided in upper plate 276 directly below the aperture of plate 281 of distributor J, when distributor J is in the dump position. The bottom end of each tube 275 terminates in an aperture provided in bottom plate 274 directly above the corresponding pin receiving pocket in pinsetting mechanism L so that the pin may be released directly thereon. Each of tubes 275 is properly oriented to extend between the two said apertures as indicated in FIG. 1 and in phantom in FIG. 29.

45 King pin conveyor H extends between the top and bottom plate 276 and 274 of storage rack K terminating in king pin delivery slide 194 (FIG. 1) which delivers king pins P_k from a resting position on conveyor H to a standing position in the king pin position (the center position) on bottom plate 274 of storage rack K. An upstanding pin receiving holder similar in structure to pin receiving holder 289 (not shown) is provided to receive and retain king pins P_k in pin storage rack K.

50 Pins P_c and P_k are retained in storage rack K by pin release plate 451 (FIG. 29). Pin release plate 451 is provided with a plurality of elongated apertures 452 corresponding in position to the apertures in lower plate 274. Plate 451 is mounted for reciprocating sliding motion on the underside of plate 274 by means of bolts provided with nylon washers passing through slots 453. At one end of each aperture 451 two frusto conical rubber bumpers 454 are provided in such manner as to extend into each aperture. In the closed position of plate 451 as shown in FIG. 29, pin P_c in tube 275 or pin P_k in the king pin holder rest with their sides in contact with the tube or with the holder and their lower end in contact with rubber bumpers 454. When it is desired to release

the pins plate 451 is slid laterally relative to bottom plate 274 (toward the bottom as shown in FIG. 29) moving bumpers 454 out of contact with pins P_c and P_k and permitting them to slide through. The means for actuating slide 451 (in pinsetting mechanism L) and described in detail in Dowd and Barrows U.S. Patent 3,063,716, issued November 13, 1962 and for this reason is indicated only diagrammatically as M herein.

Pinsetting mechanism L

The pinsetting mechanism or pie L comprises a horizontal pin orienting plate 461 mounted for vertical reciprocal travel relative to rack K on racks 414 which engage with pinions 462 mounted on lower plate 274 of pin storage rack K. Pinions 462 are connected by appropriate drive means to drive M. Plate 461 is provided with a plurality of apertures 463 having a diameter slightly in excess of the diameter of the pin and aligned precisely in the desired pin target pattern. Apertures 463 are directly in line with the apertures of bottom plate 274 or storage rack K, so that pins released from storage rack K will pass directly through apertures 463.

A parallel bottom plate 464 is provided below horizontal pin orienting plate 461 and is dependently mounted therefrom by means of a plurality of bolts 465 passing through holes provided in both plates. Bolts 465 are mounted for sliding travel through top plate 461. A plurality of rectangular apertures 466 provided in bottom plate 464 to permit passage of pins therethrough. Apertures 466 are of sufficient dimension to accommodate pin holding cups 467. Pin holding cups 467 are each formed from two cup elements 468 and 469. Cup elements 468 are hingedly mounted on a top cup holding plate 471 and cup elements 469 are hingedly mounted on bottom cup holding plate 472. Plates 471 and 472 are located between plates 461 and 464 and are mounted for parallel reciprocal lateral travel on plate 464. At the closest approach cup elements 468 and 469 form a pin holding cup 467 adapted to receive and retain the base of a pin on the upper surface thereof. Cups 467 are accurately located so that the pins when held therein are vertically above and accurately aligned with the desired target pattern. Both elements 468 and 469, and cups 467 are adapted to retract at identical rates so that the pins retained on each of them can slide out when the cup elements are retracted without any change in lateral or vertical orientation of that pin.

Each cup element 468 and 469 comprises a flat plate portion 473 and a downwardly shaped pin holding portion 474. The outer lower edge of holding portion 474 is inwardly curved to provide a clearance for the ball element in the base of the pin when a pin is deposited thereon and to provide suitable means for surrounding the neck and engaging the knob at the top of the pin during the deadwood cycle of the machine. At the rearward edge of plate portion 473 there is provided a hinge 475 attached to mounting plate 476 which in turn is in each instance bolted as indicated at bolts 477 to either top cup plate 471 or bottom cup plate 472. In the case of cup elements 471 mounting plate 476 is outwardly extending and in the case of cup elements 472 mounting plate 476 is doubled back under flat portion 473 and the hinge abutting edges are bent as shown to raise cups 469 to about the same level as cups 468. A spring element 478 is mounted in each case in association with mounting plate 476 and bears against the rear of depending portion 474 to urge portion 474 upward slightly relative to holding plate 471 or 472. The outer portion of each of elements 468 and 469 (that portion beyond hinge 475) are limited in their downward travel to a position where flat portion 473 is substantially horizontal, but are free to rotate upwardly around hinge 475 away from bottom plate 469. Springs 478 are just strong enough to deflect the empty cups upward but are

insufficiently strong to deflect the cup elements when a pin is contained thereon. Appropriately located and shaped apertures 481 and 482 are provided in cup holding plates 471 and 472 to provide clearance thereon for cup elements 468 and 469 and for the pins.

Cup holding plates 471 and 472 are mounted on lower plate 464 for lateral travel relative to each other in the following manner. Laterally extending slots 483 are provided in each plate at the position where bolts 465 pass through. Slots 483 are wide enough to clear supporting collars 484 of bolts 465 and long enough to permit full reciprocal travel. Supporting collars 484 are cylindrical pieces provided with contiguous sections having two different diameters and are adapted to slip over bolts 465 and to rest on the top of bottom plate 464. The wider lower portion 485 of collar 484 extends through plate 472 to a position just above the top surface thereof and the narrower upwardly extending portion 486 extends through plate 471 and terminates just above the top surface thereof.

Lower cup element holding plate 472 is supported on a plurality of toroidal bearing elements 487 formed of a material having a low coefficient of friction such as molded nylon. Each bearing element 487 has an inner diameter equal to the diameter of base portion 485 of supporting collar 484, and an outer diameter sufficient to contact a substantial portion of plate 472. A bearing element 487 is provided for each bolt 465.

Upper cup holding plate 471 is similarly supported on 30 toroidal bearing elements 488 which have a similar outer diameter as bearing elements 487 but which have an inner diameter equal to the diameter of the upwardly extending portion 486 of collar 484. Each bearing element 488 is supported by a steel washer 489 adapted to 35 slide over upwardly extending portion 486 of collar 484 and to rest on the shoulder between portion 486 and portion 485 of collar 484.

A bearing element 491 identical to bearing element 488 is provided around upwardly extending portion 486 of collar 484 on the top side of top plate 471. Bearing element 491 is held in place by a washer 492 which has an inner diameter equal to the diameter of bolt 465. Washer 492 is held in place by compression spring 493 which surrounds bolt 465 and abuts on one end against the top side of washer 492 and at the other end on the bottom side of upper plate 461. A similar supporting structure is provided for each bolt 465.

Lateral movement of plates 471 and 472 is provided by the mechanism shown in FIG. 22. Lower plate 464 is provided with a mounting bracket 495 adapted to receive vertically extending cup control rod 496. Cup control rod 496 which preferably has a square rectangular cross section extends through appropriate apertures provided in plates 471, 472 and 461 through lower plate 274 55 of storage rack K and is rotatably controlled by means mounted thereon (not shown) actuated by drive M. A horizontal bracket 497 surrounding rod 496 is mounted thereon and provided above plate 471. Depending from bracket 497 are mounted two vertical shafts 498 and 499 60 each provided with a rotatable bearing 501 and 502 respectively. Shafts 498 and 499 are mounted with their axes in equal distance from rod 496 on either side of rod 496 with the axes of shafts 498, 499 and rod 496 all lying on a single line. Bearing 501 engages inner slot 65 with upstanding walls 503 extending in a direction normal to the direction of travel of plate 471 mounted on plate 472. Bearing 502 engages in a similar slot with upstanding walls 504 provided on upper plate 471 parallel to slot 503. Thus any rotation of rod 496 laterally displaces plates 471 and 472 an equal distance but in opposite directions.

Plates 471 and 472 are provided with upstanding side walls 505 and 506 respectively to strengthen and stabilize the plates. Lower plate 464 is provided with an edge 75 protecting metal U section attached by bolt 508 for a

similar purpose. The bottom of bottom plate 464 is provided with a plurality of alley engaging bumper blocks 509 preferably of rubber or other elastic material of sufficient thickness to prevent contact between the downwardly extending portions 474 of cups 467 with the alley floor.

In the normal operating sequence of the machine when a new set of pins is called for sweep D clears all of the pins from alley A, while the pins contained in rack K are released (by sliding pin release plate 451) onto cups 467 of pinsetting mechanism L. Pinsetting mechanism L is permitted to descend from a position where top plate 461 is adjacent pin release plate 451 to a position where bottom plate 464 is adjacent alley A. At this point rod 496 is rotated, spreading cup member 468, 469 apart sufficient distance to clear the pins, releasing the pins onto the prescribed position on alley A. While cups 467 remain open pinsetting mechanism L is returned to the elevated position.

If the next sequence called for is a deadwood removal cycle pinsetting mechanism L with cups 467 is lowered to a position above alley A where the downwardly extending portion 474 of cups 467 are alongside the neck of the pin below the knob on top. Cups 467 are then closed by rotating rod 496 and they contact the necks of the standing pins. With the standing pins held in this way pinsetting mechanism L is returned to its elevated position carrying the standing pins with it. Sweep D which had in the meantime moved to the ball guard position thereupon continues its sweep cycle removing the deadwood and pushing it into pit D. As soon as sweep D returns to the ball guard position pinsetting mechanism L is lowered to its previous position with the bottom of the pins retained therein in contact with the alley and rod 496 is rotated to open cups 467 thereby releasing the pins. Mechanism L is then returned to its elevator position in sweep D to its raised position. Rod 496 is rotated to close cups 467 before pins are released from rack K. The distance between plates 461 and 464 is sufficient that in the deadwood cycle, the top of the standing pins picked up by the pinsetting mechanism L do not extend as far as plate 461 and therefore can not come into contact with pins that may be in storage rack K.

In certain games, particularly Abraemen and Autom-spick, it is necessary to detect the presence of standing pins. This is accomplished by the fact that the cup elements 468 are provided with springs 478 that deflect the hinged portions thereof slightly upward except when the cup 467 is carrying the weight of a pin. A microswitch 511 is mounted on top plate 471 adjacent each cup element 468 in a position to be deflected by a projection 512 provided on the side of plate portion 473 of cup element 468 when cup element 468 is depressed by the weight of a pin. Such a pin sensing device is provided for each of the cups 467. Of course this standing pin sensing means may be used not only to control the machine, but also to indicate visually through lights or the like the location of standing pins in any game.

The machine normally is set up to follow the following cycles according to the following games.

Voll—pin distributor on automatic dump:

Pin reset cycle initiated by ball detector switch.

Wiederholen Spick—pin distributor in selective dump:

Ball detector switch actuates pin selection switch plus reset cycle.

Pin selector holding relays remain in holding position until cleared by selection cancel switch at bowler's position.

Handspick—ball distributor in selective dump:

Ball detector actuates deadwood cycle.

Reset cycle initiated by reset switch at bowler's position. Reset switch also actuates pin selector switch.

Pin selector holding relays released after each reset cycle.

Abraemen—pin distributor in automatic dump:

Ball detector switch actuates deadwood cycle.

Reset cycle initiated when standing pin detector switch detects no standing pins.

5 *Autom-spick*—same as Abraemen except that the pin detector switch for the king pin position is disconnected so that the reset cycle is initiated when none of the common pins are standing whether or not the king pin is standing.

10 Obviously with minor changes in the circuitry controlling the various components many other games can be played. Likewise, while the machine as described is particularly intended for use with the German nine pin bowling game the machine itself or components thereof can be used in connection with any bowling game.

For example the same basic machine could be used for any of the ten pin games common in the United States by providing pin distributor J with ten pin receiving and holding brackets at 36° intervals rather than eight at 45° intervals and by changing the arrangement of the pin holding pockets on pinsetting mechanism L from a diamond shape to a triangular shape. Since a king pin is not used the king pin separator and king pin conveyor would be omitted. The pin orienting mechanism would be used except for candlepins where it is unnecessary since the pins are symmetrical and can be stood on either end. Of course the dimensions of the various parts would be altered to conform to the size and shape of the particular pins and balls employed in the particular game.

30 We claim:

1. In an automatic bowling pinsetting machine having means including a bowling pin elevator for sequentially raising horizontally oriented bowling pins from a lower level to a higher level, means associated with said elevator for dislodging said pins therefrom at said higher level, and means including a slide for receiving said dislodged pins; means associated with said elevator for orienting bowling pins of the type having a relatively thick body and a relatively thin neck, and for insuring that such pins enter said slide with their base portion first which comprises a pair of pivoted arms each adapted to move between an upstanding position where said arm is adapted to engage the neck of a pin after said pin has been dislodged from said elevator, and before said pin has reached said slide, and a lowered position where said arm is out of the path of said pin, link means connecting said arms whereby when one of said arms is in the upstanding position the other of said arms is in the lowered position, and pin sensing means responsive to the passage of the pin on said elevator for detecting the neck portion of the pin and erecting the corresponding arm.

2. An automatic bowling pinsetting machine as claimed in claim 1 wherein said pivoted arms are mounted for lateral rotation about parallel axes, and wherein said link means is pivotally connected to both arms.

3. An automatic bowling pinsetting machine as claimed in claim 2 wherein the length of said link means is such that when one of said arms is in upstanding position the other of said arms extends outwardly beyond the path of said pins.

4. An automatic bowling pinsetting machine as claimed in claim 2 wherein the pin sensing means comprises a pair of inwardly extending crank members each pivotally mounted for limited vertical rotation below said arms in such position that one of said cranks lies in the path of travel of the neck portion of pins on said conveyor and the other of said cranks lies in the path of travel of the body portion of a given pin, said cranks being of such length that they clear said neck portion without contact, but will contact and are deflected upwardly by said body portion, and pivoted link means connecting each said crank to its corresponding arm whereby when a crank is deflected upwardly the corresponding arm is deflected outwardly.

5. An automatic bowling pinsetting machine as claimed in claim 4 wherein each said crank member is provided with a pin contacting wheel.
